UNITED STATES PATENT OFFICE.

ARTHUR J. MOXHAM, OF JOHNSTOWN, PENNSYLVANIA.

WIRE CABLE.

SPECIFICATION forming part of Letters Patent No. 362,649, dated May 10, 1887.

Application filed October 7, 1885. Serial No. 179,206. (No model.)

To all whom it may concern:

Be it known that I, ARTHUR J. MOXHAM, of Johnstown, in the county of Cambria and State of Pennsylvania, have invented a new 5 and useful Wire Cable, which invention is fully set forth and illustrated in the following specification and accompanying drawings.

The object of this invention is to make a wire cable which shall have, with a certain 10 degree of elasticity, a greatly-increased durability, particularly when used as a traction-cable for cable railways.

The invention consists in the article of manufacture as hereinafter described, and particularly set forth in the claim.

In the accompanying drawings, Figure 1 shows in cross-section a cable composed of certain exterior and interior parts, as herein-after described. Fig. 2 shows in cross-section 20 a cable of modified interior, being made of two series of solid strands. Fig. 3 shows in cross-section a cable with a large flexible core. Fig. 4 shows in side view a piece of finished cable having a cross-section like Fig. 1. Fig. 25 5 illustrates a piece of one exterior solid strand of cable coiled or twisted before being laid up with the other strands forming the cable. Fig. 6 shows in cross-section a cable further modified having two series of strands, one of the 30 series being of solid wire and the other of finer laid-up wires around a flexible core.

In the several figures of the drawings, the letter *A* indicates a flexible core of hemp or other flexible material; *B*, a series of external 35 solid strands of wire separately formed into permanent helices, as shown in Fig. 5, before being laid up together into a cable; *b*, one series of internal solid strands of wire forming a hollow core for the external strands, *B*, as 40 shown in Fig. 2, and *c* a series of internal laid-up strands of fine wires of ordinary construction, which strands, as shown in Fig. 6, surround the flexible internal core, *A*, and are themselves covered by the external solid 45 strands, *B*.

The solid strands in all the cables shown are preferably given their separate helical set as well as laid up together in their cold state for reasons fully set forth in my pending application for process of cable-making, Serial No. 143,336, filed September 17, 1884; but a cable

composed of solid strands of wire cannot be made even cold by the ordinary method of making cables. If the straight wires be cold-twisted directly around an interior flexible 55 core, said core cannot resist the tendency of each wire not to accommodate itself to its new shape—in other words, to untwist. On the other hand, the solid strands of the cable herein described and claimed being first given 60 a helical set of suitable pitch around a mandrel, or by other machinery, before being "laid up" into a cable, such cable obviates the above-mentioned disadvantage and presents some other advantages, as below set forth. 65

It has been found in practice that great care is demanded in the use of ordinary traction-cables in motion under great tension, in order to avoid all kinks and small spherical angles, for in steel and iron of all forms constantly 70 recurring changes of form soon destroy the metal; hence the more flexible a cable is the more quickly it will yield to those changes of form to which it may be exposed or subjected by its actuating mechanism. Therefore, while 75 a certain degree of flexibility is a necessity, any excess of flexibility only increases the evil and tendency to such evil just described.

In the invention herein described and claimed the increased rigidity offered by the exterior 80 solid strands while permitting sufficient flexibility resists to a greater extent than the ordinary cable any unnecessary or undesirable change of form.

In any cable, if considered as a flexible 85 beam, it is evident that its center should preferably be flexible, such center being its neutral axis. It is also evident that from such axis the flexibility should decrease toward the exterior of the cable until the maximum rigidity is reached at the external surface of the cable. When, therefore, in the cable herein described more than one series of solid strands are required to secure the desired strength and diameter of cable, this result can manifestly be obtained by making each internal series of such strands smaller in diameter than its contiguous exterior series until the center or core is reached, which center or core should preferably be, as is commonly the case, of some much more flexible material than that used for the strands proper. 100

The same result is also practically obtained when but a single series of solid strands is coiled, as herein described, over or upon a central flexible core. The interior may, therefore, 5 consist, when desired, of either a solid or a laid-up strand of suitable diameter, or of any interior of suitable material without departing from the principle of this invention, such core being made of material having greater 10 flexibility than its outlying strands.

The explanations above made equally apply if the cable be considered as subjected to a direct tensile strain only, for in such case the first resistance to change of form is that 15 of the friction of the exterior strands, one against the other. The tendency ensuing is to compression of the interior and center. If the friction aforesaid be excessive, the outside strands will rupture before the center is com- 20 pressed; hence excessive friction of the exterior strands should be avoided. If the friction of such strands be reduced within requisite limits, so as to permit the interior strands or core to take part in resisting the strain, 25 then such interior should be capable of yielding to a sufficient extent to at least take its proper part in the general resistance. If an absolutely-rigid core be used, the whole strain tending to rupture, or the whole resistance to 30 such strain, will fall upon the exterior strands in case of excessive friction between such strands, or upon the interior or core in case of deficient friction between the exterior strands. In neither of these cases, therefore, would the 35 cable be homogeneous; but by making the flexibility such that it continuously increases from the exterior to the interior, as is the case in the arrangements of strands herein described, the desired homogeneity is attained.

40 In the construction of cables with solid exterior strands of wire, such as are herein described and claimed, it is of importance to observe the following points: Said solid strands must not exceed a given or predetermined de- 45 gree of flexibility; hence the diameter for each wire becomes a fixed thing or constant as soon as this limit is reached; and with regard to a flexible core it would manifestly be a serious error to make the flexible core of a diameter 50 so large as to exceed too much the diameter of the neutral axis proper, as is illustrated in Fig.

3. Therefore the space contained between the exterior strands and any core, in consequence of thus fixing their respective diameters, may be filled up with two or more internal series 55 of strands of different diameters—that is, decreasing from the circumference toward the center—as hereinbefore explained. Should any portion of the space to be filled, however, be too large for one series of interior solid 60 strands and not large enough for two such series, such space may be filled with a single series of strands of suitable diameter, made of twisted or laid-up fine wires—such as are used for strands of ordinary cables—as is illustrated 65 in Fig. 6. The desired flexibility of cable, together with the necessary occupation of space, can thus always be secured with great accuracy of design.

In wire-rope cables as commonly constructed 70 the interlocking of the wires composing the outer strands induces excessive friction, so great, indeed, as to throw the greatest strains and tension to which the cable is subjected upon these exterior strands. The elongation 75 of such cables previous to rupture under excessive strains, it is known from experience, is very small; but by using solid strands, as herein described, for exterior strands, such elongation is increased, and the freedom from 80 excessive friction between said strands permits the internal parts of the cable to bear their proper proportional parts of the strain.

I am aware that it has been proposed to make a hollow lightning-conductor of solid twisted 85 wires, and such an article I do not claim, but limit myself to the cable herein described, made of solid exterior strands and interior of more flexible construction, whether of one or more of the forms of such described interiors. 90

Having thus fully described my said new form of cable as of my invention, I claim—

As a new article of manufacture, a traction wire cable composed of helically-twisted solid strands of wire laid up together and combined, 95 as described, with a more flexible interior or core, substantially as and for the purposes set forth.

ARTHUR J. MOXHAM.
